UNITED STATES PATENT OFFICE.

FRANK L. BOWEN AND WILBURN I. COOK, OF BIRMINGHAM, ALABAMA.

PACKING-RING.

1,152,277.

Specification of Letters Patent. Patented Aug. 31, 1915.

Application filed July 29, 1914. Serial No. 853,980.

To all whom it may concern:

Be it known that we, FRANK L. BOWEN and WILBURN I. COOK, citizens of the United States, residing at Birmingham, in the county of Jefferson and State of Alabama, have invented new and useful Improvements in Packing-Rings, of which the following is a specification.

Our present invention relates to improvements in packing rings and has particular application to an expandable ring.

In carrying out the present invention, it is our purpose to provide an expandable packing ring which will be found especially useful in packing the pistons of internal combustion engines, steam engines, ammonia compressors and analogous devices and the plungers of pumps and which will embody two split annuli disposed one about the other and surrounding the piston or plunger, and means holding said annuli against relative turning movement so as to preserve the efficiency of the ring.

It is also our purpose to provide a packing ring of the class described which will embrace the desired features of simplicity, efficiency and durability, which may be manufactured and marketed at a minimum expense and which will wear a relatively long period of time.

With the above and other objects in view, the invention consists in the construction, combination and arrangement of parts hereinafter set forth in and falling within the scope of the claim.

In the accompanying drawing: Figure 1 is a view in elevation of a packing ring constructed in accordance with the present invention. Fig. 2 is a transverse sectional view therethrough. Fig. 3 is an enlarged fragmentary sectional view showing a modified form of the invention.

Referring now to the drawing in detail, 1 designates an annulus split as at 2 and 45 having a rabbet or groove 3 formed in the periphery thereof and opening onto one edge. In the present instance, the bottom wall of this rabbet or groove is eccentric to the axis of the annulus and seated within 50 the groove 3 is a second annulus 4 split as at 5 and having the split portion thereof disposed at a point diametrically opposite

the split in the annulus 1. The inner wall of the annulus 5 conforms to the configuration of the bottom wall of the groove or rabbet 3 so that when the annuli are assembled the outer surface of the annulus 4 lies flush with the outer surface of the annulus 1.

In practice, the annulus 1 is sprung into 60 the groove in the piston or plunger and the annulus 4 sprung into the rabbet in the annulus 1 and the split portions of the annuli disposed at diametrically opposite points. By means of the eccentric wall of 65 the rabbet and similar inner wall of the annulus 4 relative rotation of the annuli is prevented, while the ring as a unit will expand and contract incident to the split annuli. 70

In the modified form of the invention illustrated in Fig. 3, the bottom wall of the rabbet is arranged concentrically of the axis of the annulus, while the inner wall of the annulus 4 is similarly arranged and 75 the confronting walls of the annuli are formed with registering grooves 6 constituting an opening to receive a dowel pin 7 whereby relative movement of the annuli, when the packing ring is applied, is prevented. This construction whereby relative movement of the annuli is prevented, is of vital importance, inasmuch as grease and other foreign matter that accumulates between the annuli subject the latter to undue 80 wear if they are permitted any torsional or sliding movements relatively. 85

While we have herein shown and described certain preferred forms of our invention by way of illustration, we wish it 90 to be understood that we do not limit or confine ourselves to the precise details of construction herein described and delineated, as modification and variation may be made within the scope of the claim without departing from the spirit of the invention. 95

We claim:

A packing ring comprising a split eccentric ring of L-shaped formation in cross 100 section, a second split eccentric ring rectangular in cross section and adapted to fit on the flange of said first ring, the splits thereof being diametrically opposite when

2
assembled, each ring arranged in their contacting periphery with a registering semi-circular groove extending in a lateral direction from the side of said rings when assembled, and a pin adapted to be inserted in said lateral groove whereby relative movement between said rings is obviated.

In testimony whereof we affix our signatures in presence of two witnesses.

FRANK L. BOWEN.
WILBURN I. COOK.
